4 Claims. (Cl. 132—125)

ABSTRACT OF THE DISCLOSURE

Electrically conductive bars are mounted along the teeth of a hair comb with dielectric material positioned between the electrically conductive bars and the teeth of the comb for the purpose of generating electrostatic charges.

This invention relates to an improved construction for a hair comb assembly and particularly to an assembly in which an electrostatic charge is generated when used in combing hair.

Many women find that in trying to arrange and to style fashionably their hair, they encounter various problems for a number of causes. One cause is the natural state of the hair. Another is self-created changes in the hair, and still another is environment conditions affecting the hair.

Some of the abnormal conditions which may exist in hair in its natural state are that, it may be too fine or too coarse, too dry or too oily, too porous or too impervious, or too curly or too straight. These conditions usually do not exist alone, but two or more conditions exist in combination with each other.

Many women change the natural state of their hair by one or more methods, such as, tinting, dyeing, or bleaching, or applying permanent wave solutions. One of the latest styles is the bouffant style which requires a certain amount of "ratting" to produce a puffed affect. These self-created changes provide adverse affects on the hair in that the changes cause the hair to become dry, porous, brittle or reduce the natural oils in the hair. The "ratting" of hair for bouffant hair fashions causes the hair to break and to split. All of these conditions of the hair considerably lessen the body of the hair making it harder to style and to arrange fashionably and to keep hair in place without excessive use of oils, creams and hair sprays.

It is apparent that if the hair lacks body, any measures taken to style and to arrange the hair will be less effective. It is therefore a principal object of this invention to provide a hair comb assembly in which combing of the hair with the assembly creates an electrostatic charge which causes the hair to stay in place longer, to hold a desired set and to add body to a bouffant hair style with less "ratting" and hair spray.

Environmental conditions affect the hair in that the hair gets dirty from atmospheric dust which settles on the hair. In addition, dirt is often transferred to the hair from hands and clothing under certain conditions especially in certain types of work. Application of hair cream or hair spray tends to hold dirt and dust in the hair which may normally fall off or be blown away. Also, many women are plagued with dandruff and dry scalp conditions, and these women have flakes or scales in the hair which are symptomatic of the condition. The scales or flakes in the hair detract from the appearance of the hair so that women with these conditions wash their hair more often to maintain its appearance. Therefore, it is another object of the instant invention to provide a hair comb assembly in which an electrostatic charge is built up in the comb assembly during combing and the comb assembly collects foreign particles from the hair, such as, dirt, dust, excess hair spray, dandruff scales and other foreign particles, thus cleaning the hair.

2

It is a further object of this invention to provide a simple and economical construction for a comb assembly which may be used to comb hair and generate electrostatic charges.

5 Other objects and uses of the herein disclosed invention will become readily apparent to those skilled in the art upon a perusal of the following specification in light of the accompanying drawing, in which:

FIGURE 1 is a perspective view of a comb assembly embodying the herein disclosed invention;

FIGURE 2 is a cross sectional view taken on line 2—2 of FIGURE 1;

FIGURE 3 is a cross sectional view of a portion of the comb assembly shown in FIGURE 1 taken on line 3—3 of FIGURE 2; and

FIGURE 4 is an exploded view of the comb assembly shown in FIGURE 1 showing the relationship of the various parts.

Referring now to the drawing, it may be seen that a 20 comb assembly generally indicated by numeral 10 and embodying the herein disclosed invention generally consists of a base 12, a pair of identical dielectric blocks 14 and 16, a pair of identical electrical conductive metal bars 18 and 20, and a dielectric comb 22.

The base 12, in this instance, is a molded part made of phenol formaldehyde resin which is an electrical insulating material. The base includes a receptacle portion 24 which has a comb receiving aperture 26. Formed integral with the receptacle portion is a pair of wings 28 and 30 25 which are parallel to each other and to the axis of the base. A handle 32 is formed integral with the receptacle portion and provides a convenient means for holding the comb assembly.

The comb 22, in this instance, is made of molded hard 35 rubber. The comb includes a back 34 and a plurality of teeth 36 formed integral with the back and perpendicular thereto. Each of the teeth, it may be seen in FIGURE 2, has a waist portion 38 adjacent to its outermost edge so that there is somewhat enlarged portion 40 at the outer 40 end of each of the teeth. This particular construction of the teeth is helpful in retaining an electrostatic charge on the teeth of the comb.

The blocks 14 and 16 are identical in construction, and 45 in this instance, the blocks are made of methyl methacrylate resin. The blocks 14 and 16 have bodies 42 and 44, respectively. The bodies 42 and 44 have embrasure-like surfaces 46 and 48 respectively formed therein to define hair engaging edges 50 and 52 respectively. The block bodies 42 and 44 with back 34 of the comb are positioned 50 in the comb aperture 26 of the receptacle portion of the base as may be seen in FIGURE 2. The blocks and the comb are held in the receptacle portion by a suitable adhesive which, in this instance, is an epoxy resin.

The metal bars 18 and 20 are elongated, and each has 55 a generally U-shaped cross section. The bars 18 and 20 are mounted on wings 28 and 30, respectively, and they are held onto their respective wing by a suitable adhesive which in this instance is also an epoxy resin. It should be noted that the bars are on opposite sides of comb 22, and they are substantially transverse to the teeth of the comb. The blocks 14 and 16 with their hair engaging edges 50 and 52 respectively, are positioned between the adjacent bars and the comb with the embrasure-like surface is adjacent to the comb so that the edges are spaced 60 from the comb.

When the instant comb assembly is placed into use, the operator of the assembly holds the assembly by the handle 32, and the teeth of the comb are placed in the hair and moved relative to the hair so that the hair engages 70 with block 14 or block 16 and the metal bar which is adjacent to that particular block. The movement of the

comb and the block and the metal bar relative to the hair causes an electrostatic charge to be generated in the hair as well as on the comb and the block. It should be noted that the embrasure-like surface of the block defines a gap between the comb and the block which aids materially in the generation of the electrostatic charge. The particular construction of the teeth of the comb aids in retaining the electrostatic charge on the teeth rather than allowing a charge to run off the end of the teeth to be discharged. This charge which is created by the bar and the gapping between the hair engaging edge and the teeth causes foreign particles to be collected on the block and the teeth of the comb. It should be noted that the blocks extend over a portion of the lengths of the teeth of the comb so that foreign particles are held between the teeth and the block and not on the back of the comb where foreign particles are not easily removed. The instant comb assembly may be readily cleaned by simply washing in water, and there is no build up of foreign particles at the back of the comb where it is difficult to remove the particles.

It is found that the use of the present device in the hair not only removes foreign particles from the hair but it also improves the body of the hair so that in some instances ratting is not necessary to give an improved appearance.

Although it has been found that an optimum construction is one in which the comb is made of hard rubber and the block made of methyl methacrylate resin, the instant device operates well when the comb is made of methyl methacrylate resin and the block is made of hard rubber. It has also been found that the present device is also operative when the block are made of a material selected from a group of materials consisting of, polyethylene, vinyl acetate copolymer and vinyl chloride copolymer.

It is apparent that the construction of the subject comb assembly is very simple and the parts may be inexpensively manufactured by molding and the metal parts may be stamped out of metal such as aluminum or any other suitable electrically conductive material.

Although a specific construction of the instant invention has been shown and described in detail above, it is submitted that those skilled in the art may make various modifications and changes in the construction shown herein without departing from the spirit and scope of the present invention. It is to be expressly understood that the present invention is limited only by the appended claims.

What is claimed is:

1. A comb assembly comprising, in combination, a base composed of electric insulator material having a receptacle portion, a comb fixed in the receptacle portion of the base, said comb having a plurality of teeth, a pair of elongated electrically conductive bars being mutually electrically insulated mounted on said base on opposite sides of the comb and being positioned substantially transverse to the teeth of said comb, and a non absorbent dielectric block positioned between each of said bars and the comb, each of said blocks having an elongated edge substantially parallel to the bar spaced from the comb

and its respective bar to provide a hair engaging edge for the block for generating electrostatic charges on the hair passing over the edge to collect foreign particles from the hair.

5 2. A comb assembly comprising, in combination, an elongated receptacle portion having a pair of outwardly extending wings formed integral with opposite edges of the receptacle portion, an elongated electrically conductive metallic bar fixed to each of said wings, a comb having a plurality of teeth fixed in the receptacle portion and having the teeth substantially transverse to the bars, and a dielectric block positioned between each of the metal bars and the comb, each of said blocks having an elongated edge substantially transverse to the teeth of the comb to provide an engaging edge for contacting hair as the comb passes through the hair to collect foreign particles from the hair.

10 3. A comb assembly comprising, in combination, an elongated molded phenol formaldehyde resin base, said base having a receptacle portion and a handle formed integral therewith, a pair of wings formed integral with the receptacle portion and being positioned on opposite sides of the receptacle portion, a hard rubber comb having a plurality of teeth fixed in said receptacle portion with the teeth being substantially transverse to the wings of said receptacle portion, each of the teeth of said comb having a reduced portion adjacent to its outermost end for retaining an electrostatic charge on said comb, an elongated electrically conductive metal bar mounted on each of said wings in a position substantially transverse to the teeth and a methyl methacrylate resin block positioned between each of said bars and the comb, each block having an embrasure-like surface adjacent to the comb to provide a hair engaging edge spaced from the comb and the respective metal bar for contacting hair passing through the comb and engaging the metal bar to collect foreign particles from the hair onto the block and the comb.

15 4. A comb assembly comprising, in combination, a base composed of electric insulator material having a receptacle portion, a comb fixed in the receptacle portion of the base, said comb having a plurality of teeth, an elongated electrically conductive bar mounted on said base on one side of the comb and being positioned substantially transverse to the teeth of said comb, and a non absorbent dielectric block positioned between said bar and the comb, the block having an elongated edge substantially parallel to the bar spaced from the comb and the bar to provide a hair engaging edge for the block for generating electrostatic charges on the hair passing over the edge to collect foreign particles from the hair.
